SHIPPING CONTAINER

Frederick E. Ullman, Winnetka, Ill., assignor to In-
land Steel Company, Chicago, Ill., a corporation
of Delaware

Filed Mar. 28, 1967, Ser. No. 6,411

Term of patent 14 years

(Cl. D9—170)

FIG. 1.

FIGURE 1 is a side elevational view of a shipping container embodying my new design.

FIGURE 2 is a top plan view on a reduced scale showing the outline of the shipping container shown in FIG. 1.

FIGURE 3 is a fragmentary vertical section on an enlarged scale of the container shown in FIG. 1, here depicting the chime connection between the lower end member and the side wall, it being understood that the chime connection between the upper end member (not shown) and the side wall is the same.

The instant design for the shipping container is characterized by the provision of a side wall having a repeating pattern of alternate beads and furrows, the repeating pattern being interrupted at two axially spaced locations along the axial length of said side wall to define two axially spaced circumferential wall portions which are devoid of beads and furrows and with the repeating pattern of alternate beads and furrows adjacent each extremity of the side wall having a progressive reduction in bead diameters.

I claim:

The ornamental design for a shipping container, substantially as shown and described.
